LYMAN MELVIN JONES AND ROBERT HENRY VERITY, OF TORONTO, ONTARIO, CANADA,
ASSIGNORS TO MASSEY-HARRIS CO., LTD., OF TORONTO, CANADA.

LIFTING DEVICE OF MOWER CUTTER-BARS.

1,077,351.

Specification of Letters Patent.

Patented Nov. 4, 1913.

Application filed September 20, 1909. Serial No. 518,631.

To all whom it may concern:

Be it known that we, LYMAN MELVIN JONES, president of the Massey-Harris Company, and ROBERT H. VERITY, superintendent of the said company, both of the city of Toronto, in the Province of Ontario, Canada, have invented certain new and useful Improvements in Lifting Devices of Mower Cutter-Bars, of which the following is a specification.

This invention relates to improvements in the devices employed in mowers to raise and lower the cutter bar.

The device on which this present invention is an improvement comprises a chain attached to the cutter bar and to a pivoted quadrant lever adapted to be rocked either by hand lever or a foot lever.

Frequently when the cutter bar is lowered to its full normal extent there is a demand for a further drop to allow the cutter bar to follow a depression in the ground. We provide for this by utilizing as the forward side of the notch in the retaining quadrant of the hand lever a spring actuated stop which will yield to allow the hand lever to rock forward to a limited extent and with it the quadrant lever and chain. Formerly when no yielding stop was employed the chain of the quadrant lever had to be of sufficient length to allow of the extreme drop of the cutter bar and to take up this extra length of chain the quadrant lever required to be made with the face on which the chain was taken up of a decided convex curve. The hand lever also had to stand so far forward when the required amount of chain was given to enable the cutter bar to drop to its limit, that it was in an awkward position to reach.

With our improved construction as the abnormal drop is provided for by the rocking of the quadrant lever against the yielding resistance of the stop less chain is required and we are therefore enabled to make the winding face of the quadrant lever substantially straight which makes the lifting operation easier as the leverage of the quadrant is most effectual when the power of the operator is least advantageously applied and vice versa. We are also enabled to set the hand lever so that when the cutter bar is in its normal lowered position it is easily reached and only occupies a far forward

position when the cutter bar drops to an abnormal extent.

Figure 1 is a side elevation of a lifting device constructed in accordance with our invention, the parts being in normal position. Fig. 2 is an end view of the same, partly in section. Fig. 3, is a view similar to Fig. 1, showing the quadrant lever rocked by the foot lever. Fig. 4 is a view similar to Fig. 2 with the parts in the position shown in Fig. 3. Fig. 5 is a view similar to Fig. 3 showing the quadrant lever further rocked by a movement of the hand lever. Fig. 6 is a plan view, partly in section, showing the parts in normal position. Fig. 7 is a view similar to Fig. 1, looking at the other side.

In the drawings like letters of reference indicate corresponding parts in the different figures.

The lifting device in its main features is old in the art, but its construction and mode of operation must be described to render description of the novel features rightly understandable.

A is the tongue of a mower. B is a quadrant lever fulcrumed thereon. Secured to the upper part of this quadrant lever is a chain C which is intended for connection with the cutter bar of the mower. The operative face of the quadrant lever is grooved to engage the chain. (See Figs. 2 and 6.) By the rocking of the lever B a pull may be imparted to the chain to move the parts to which it is connected. The quadrant lever B is provided with a foot lever D and also with a hand lever E, which operates as hereinafter described. A retaining quadrant F is provided by means of which the lever E may be held as adjusted. A spring G is also provided connected at one end to the quadrant lever B and at the other to the tongue or other suitable part of the frame. This spring tends to counterbalance the weight of parts to which the chain C is connected.

The construction by which we arrange that the quadrant lever may be operated either by hand or foot is as follows:—The hand lever has a hollow boss H formed thereon. In the lever and in this boss is suitably guided a notched slide I. Within the boss is a coil spring e which normally tends to press the slide toward the left as shown in Figs. 2 and 4 of the drawings. On the notched retaining quadrant F is formed

a cam face J against which the spring c presses the notched slide I. The quadrant lever B has two shoulders a b formed thereon. The part of the quadrant lever B between the shoulders a and b is adapted to work through the notch h in the slide I. When the hand lever H is pushed to its forward position the slide I rides upon the high part i of the cam J and the notch in the slide is thus brought into a position to enable the part of the quadrant lever between a and b to play through it (see Figs. 1, 2 and 6) and the quadrant may be rocked by the foot lever to the position shown in Fig. 3. A further lift to the quadrant lever may then be imparted by drawing the hand lever backward whereupon the slide I rides down the cam J being pressed by the spring c and the unnotched portion of the slide is brought into the path of the shoulder b with which it engages, which shoulder has of course been brought to the rear of the slide I by the previous operation of the foot lever (see Figs. 3, 4 and 5). The cutter bar may now be raised to its limit by the further drawing back of the lever E and held raised by engaging the catch d behind the shoulder k on the quadrant F as shown in Fig. 5. When the parts are in the position shown in Figs. 1 and 2 the first rocking movement to the quadrant lever also may be imparted by the hand lever, as the shoulder a is then in contact with the part j of the hand lever as shown. When the parts are in the position shown in Fig. 7 the spring actuated latch d on the hand lever E lies in a notch formed at the front of the retaining quadrant F. The forward side of this notch, however, instead of being formed of an immovable part integral with the quadrant is formed by a yielding spring pressed stop comprising a plunger K sliding in a casting L preferably cast integral with the retaining quadrant. This plunger is formed with a stem e which extends out through the casing and may have a pin f passed through it to limit the forward movement of the stem under the action of the coil spring g which engages the plunger and the end of the casing L. When the parts are in the position shown in Fig. 1 of the drawings the quadrant lever B has rocked sufficiently far forward to enable the cutter bar to assume its normal cutting position. If, however, a depression is encountered by the machine which necessitates a further drop of the cutter bar the weight of the parts connected to the chain C is sufficient to rock the quadrant lever B and the hand lever against the resistance offered by the spring actuated stop or plunger K, the part B moving through the notch h in the slide I and a sufficient amount of chain is thus given to meet the requirements of the case. Except under these abnormal conditions the

hand lever stands in a position sufficiently near the vertical to be within convenient reach of the operator's hand.

As only a sufficient amount of chain is needed to reach from the quadrant lever to its connections on the cutter bar without any slack the convex face ordinarily employed on the quadrant lever may be dispensed with as there is less chain to be gathered up and it is found that by making the chain engaging face of the quadrant lever substantially straight as shown it becomes considerably easier to lift the cutter bar owing to the effectiveness of the leverage obtained.

We do not desire, of course, to limit ourselves to the exact arrangement of the yielding spring pressed stop which tends to limit the forward rock of the quadrant lever, as other arrangements might be devised which would answer the purpose of our invention.

What we claim as our invention is:

1. In a lifting device for mower cutter bars the combination of a quadrant lever fulcrumed on the frame of the machine; a chain secured to the said quadrant lever for connection to a mower cutter bar; a yielding spring pressed stop supported from the frame of the machine and determining the normal downward swing of the quadrant lever and a part connected with said quadrant lever and adapted to engage said stop.

2. In a lifting device for mower cutter bars the combination of a quadrant lever fulcrumed on the frame of the machine; a hand lever adapted to operate said quadrant lever; and a retaining quadrant for the hand lever provided with a yielding spring pressed stop supported from the frame of the machine and limiting the normal forward movement of the hand lever.

3. In a lifting device for mower cutter bars the combination of a quadrant lever fulcrumed on the frame of the machine and having a substantially straight chain engaging face; a chain secured to said quadrant lever for connection to a mower cutter bar; and a yielding spring pressed stop supported from the frame of the machine and determining the normal downward swing of the quadrant lever.

4. In a lifting device for mower cutter bars the combination of a quadrant lever fulcrumed on the frame of the machine and having a substantially straight chain engaging face; a hand lever adapted to operate said quadrant lever; and a retaining quadrant for the hand lever provided with a yielding spring pressed stop supported from the frame of the machine and limiting the normal forward movement of the hand lever.

5. In a mower the combination of a quadrant lever fulcrumed on the frame of the

machine; a hand lever pivoted on the same fulcrum; a notched slide suitably guided in the hand lever transverse of the quadrant lever; a part on the quadrant lever adapted to work through the notch, a shoulder being formed thereon; a spring normally tending to press the slide endwise to bring its unnotched portion into the path of the shoulder of the quadrant lever; a retaining quadrant for the hand lever mounted on the frame; a stationary cam on said retaining quadrant with which the said slide en-

gages so that it is given an endwise motion as the hand lever is rocked; and a yielding spring pressed stop supported from the frame of the machine and limiting the normal forward movement of the hand lever. 15

Toronto, this 10 day of September, 1909.

LYMAN MELVIN JONES.

ROBERT HENRY VERITY.
